UNITED STATES PATENT OFFICE.

JOHN D. SMITH, OF MARYSVILLE, CALIFORNIA.

BURGLAR ALARM.

Application filed September 1, 1921. Serial No. 497,525.

To all whom it may concern:

Be it known that I, JOHN D. SMITH, a citizen of the United States, residing at Marysville, in the county of Yuba and State of California, have invented certain new and useful Improvements in Burglar Alarms; and I do declare the following to be a full, clear, and exact description of the invention, such as will enable others skilled in the art to which it appertains to make and use the same.

This invention relates to an improved burglar alarm, and it has for its principal object to provide a device of this class embodying two independent successively operable circuits, one of which is controlled by a closure, such as a door, a window, or what not; and as soon as this circuit is broken, the second, which is the signal operating circuit, is automatically operated to sound a bell or the like and continue to do so until this circuit is broken by manually controlled means, as hereinafter described and claimed.

Another object of the invention is to provide a burglar alarm embodying the aforesaid two circuits, the primary or closure controlled circuit serving to actuate a trip which normally supports the movable element of a switch in a raised inoperative position, this switch when closed serving to close the secondary or signal circuit.

Another object of the invention is to provide a burglar alarm embodying the circuits mentioned, the aforesaid switch constituting a part of both of said circuits and thereby providing a novel arrangement of parts wherein when the secondary circuit is closed, the primary circuit is absolutely broken, this result not being obtained until the switch is rendered effective.

A still further object of the invention is to provide an arrangement wherein the trip and switch referred to are enclosed in a housing which is concealed to prevent the intruder from obtaining access thereto and rendering the switch which controls the secondary circuit inoperative.

Other objects and advantages of the invention will be apparent during the course of the following description.

In the accompanying drawings forming a part of this specification and in which like numerals are employed to designate like parts throughout the same:

Figure 1 is a sectional view through the mechanism casing showing the mechanism

in elevation and the parts in their normal inoperative position.

Figure 2 is a sectional view including the electric circuit and showing the parts in positions they take when the secondary or signal operating circuit is closed.

Figure 3 is a sectional view taken substantially on the plane of the line 3—3 of Fig. 1.

In carrying out the invention, I make use of an asbestos lined housing or container 1 which I arrange in a place where it will be practically concealed from persons entering the house. By preference however, it will be arranged in some convenient position to enable the occupants of the house to obtain easy access thereto for resetting the signal closing switch, that is, for rendering this switch effective. Among other parts which are arranged in the container is an upstanding bracket 2 embodying spaced uprights 3, one of which serves to support a pair of electro-magnets 4. The exact manner of connecting these magnets with this upright is not shown as this may be accomplished in any suitable way. It is of course understood that the magnets will be insulated from the upright on which it is arranged by means of a strip of material 5. As a matter of fact, insulating material will be employed at all necessary points to prevent possible short-circuiting and it will hardly be necessary to point out just where such material is located.

As before indicated, a vertically disposed armature 6 is co-operative with and attracted by the magnets and this armature is connected with a suitable spring 7 which serves to disengage it from the magnets and cause it to resume its original position after the magnets are deenergized. It is to be pointed out here the armature 6 constitutes what may be conveniently termed a trip, and has its upper free end directed laterally as indicated at 8 so that it will effectively serve in this capacity. It may be stated here that this trip serves to support and retain a substantially U-shaped member 9 in the raised position indicated in Fig. 1, this member being pivoted at its ends to the upper ends of the uprights of the aforesaid bracket and having its intermediate or connecting portion rested on the laterally directed end of the trip. One of the arms of the part 9 carries a blade 12 which is designed for co-action with the contact clip 13 supported on one of the uprights of the brackets. It is

obvious that these parts 12 and 13 form an

ordinary knife switch which, as before indicated, constitutes a part of a signal operating circuit to be hereinafter described. Part 9 is, when the trip is disengaged therefrom, lowered by gravity to engage the blade with the clip so as to close the switch and it remains in this position until it is raised by manually controlled means. In the drawing, this means comprises a flexible cord 14 which 10 is connected with the part 11 and is passed over pulleys 15 arranged inside of the aforesaid housing 1. It is understood that the free end of this cord which is arranged on the outside of the housing is extended down 15 toward the floor so that it will be at a convenient place where it can be gripped by a person standing on the floor for the purpose of elevating the member 9 and again engaging it with the trip. To permit the arm to 20 readily drop to its operative position and to prevent the weight of the cord itself from interfering with the dropping, a coiled spring 16 is connected with the cord and serves to lift the cord after it is released. I 25 may mention here that suitable brackets or the like 17 are arranged inside of the housing for the purpose of supporting the aforesaid pulleys 15. It is also to be pointed out that in addition to the aforesaid parts, there 30 is also arranged in the housing a laterally disposed contact member 18 which is connected with the extreme upper end of one of the uprights of the bracket 2 and has its outer extremities directed laterally as indicated at 19 and bevelled so that when the 35 part 9 is raised, by pulling the cord 14 downwardly, this bevelled end will engage the same for a purpose to be hereinafter set forth.

40 As before intimated, two independent circuits are employed with my arrangement and one of these circuits, which includes the wires 20, 21, 22 and 23, may be termed the primary circuit. This circuit is controlled, 45 as before pointed out, by a closure, either a door D or window sashes S which are equipped, as already pointed out, with a special circuit closing element or switch which will be described in detail as the description goes on. By carefully tracing the 50 wires just mentioned, it will be seen that the one indicated by the numeral 20 leads from this special circuit closing device to the uprights 3 on the aforesaid bracket, electrifying this upright, which, as is obvious, is composed of suitable conducting material. Since 55 the closure and the electro-magnets 4 are connected with this upright through the medium of a wire 24 and are connected with each other by a wire 25, they are energized 60 when this primary circuit is closed. A wire 26 leads from the upper magnet to a pin 27 which serves to connect the aforesaid member 18 with the bracket. Hence, when 65 the circuit is closed the current will pass and dispose the mechanism in the housing in

through this pin and then through the member 18 and inasmuch as this member is engaged with the aforesaid arm 9 the current will pass through this arm 9, and through the wire 21 which is connected therewith 70 and leads through the day switch 28 and wire 22 to the battery 29 and finally through the wire 23 to the starting point.

Hence, the passage of the current through the primary circuit is understood. The secondary or signal operating circuit also includes the aforesaid wires battery 21 and 22 together with the additional wires 30 and 31 which are connected with and operate the bell 32. As previously pointed out, the 75 switch which is made up of the aforesaid blade 12 and clip 13 constitutes a part of this last-named circuit and it is obvious that so long as the part 9 is supported in the position indicated in Fig. 1, this circuit is 80 broken. However, as soon as the primary circuit has been completed and acts on the trip 6 in such a way as to permit the part 9 to be lowered, the knife switch just referred to is closed and this secondary circuit is 85 completed so that the bell 32 is sounded and is continuously sounded until the switch elements 12 and 13 are disengaged. The manner in which wiring from the window sashes 90 S may be connected with the wires in the circuits already described is plainly shown in Fig. 2 and inasmuch as the exact arrangement of the wires is immaterial so far as this invention is concerned, such arrangement of 95 wires will not be discussed.

The operation of the improved alarm is doubtless clear after reading the foregoing description. Yet, it may be advisable to insert at this point a brief review of such operation. To this end, it will be seen that 100 during the day time, the key-controlled switch 28 which, as indicated, may be constructed in any suitable way, is arranged so that opening and closing of the door or window will not affect the electric circuits. 105 However, at night, the switch 28 is "turned on" and in case either the door or the windows are opened and an attempt is made, by unauthorized persons, to enter the house by this method, it will be seen that the primary 110 circuit which is controlled by such closures, will be closed. In so doing, the aforesaid magnets 4 will be energized and will attract the trip 6, thus moving the latter in such a 115 way as to disengage its laterally bent end from the part 9. The latter will then drop by gravity and in this way break the circuit just referred to. On the other hand, the signal operating circuit will now be completed because the blade 12 will be engaged 120 with the clip 13 and this circuit will be rendered effective and will remain so until the hanging portion of the cord 14 is gripped and pulled downwardly to elevate the part 9 125 and dispose the mechanism in the housing in 130

its original state, that is, as indicated in Fig. 1. Hence, it will be seen that when the door is again closed, or even if the primary circuit is destroyed, the remaining circuit will still remain effective and will ring the bell until the occupants of the house care to disengage the signal by operating the manually controlled means referred to above.

By carefully considering the description 10 in connection with the drawings, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the 20 invention. However, I wish it to be understood that minor changes coming within the scope of the subjoined claims may be resorted to if desired.

I claim:

25 A circuit maker and breaker for primary and auxiliary circuits comprising a support, an electro-magnet carried by said support and insulated therefrom, a latch form-

ing armature yieldably mounted in operative relation to said magnet and moved out of its 30 normal position when the electro-magnet is energized, an arm of conducting material connected with said support and insulated therefrom, the winding of the electro-magnet having one end thereof connected with 35 said arm and its other end adapted for connection with one side of a source of energy, a contact carried by said support in insulated relation thereto and adapted for connection with a lead wire of an auxiliary circuit, and a swinging arm of conducting material pivotally connected with said support in insulated relation thereto and adapted for connection with a lead wire from the other side of the source of energy, said swinging 40 arm being held in an open position and in engagement with the first mentioned arm by said armature until the electro-magnet is energized and draws the armature out of its normal position, the swinging arm then 45 having movement into engagement with said contact to close the auxiliary circuit.

In testimony whereof I have hereunto set my hand.

JOHN D. SMITH.
